UNITED STATES PATENT OFFICE.

HERMANN C. NAUMANN, OF DETROIT, MICHIGAN, ASSIGNOR TO PENINSULAR STAMPING COMPANY, OF DETROIT, MICHIGAN, A CORPORATION OF MICHIGAN.

DESIGN FOR A SECURING-CLIP FOR SPRINGS.

57,851.

Specification for Design.

Patented May 10, 1921.

Application filed August 13, 1920. Serial No. 403,413. Term of patent 14 years.

To all whom it may concern:

Be it known that I, HERMANN C. NAUMANN, a citizen of the United States of America, residing at Detroit, in the county of Wayne and State of Michigan, have invented a certain new, original, and ornamental Design for a Securing-Clip for Springs, of which the following is a specification, reference being had therein to

the accompanying drawing, forming part thereof.

The figure is a perspective view of a securing clip for springs, showing my new design.

I claim:

The ornamental design for a securing clip for springs as shown.

HERMANN C. NAUMANN.
